UNITED STATES PATENT OFFICE.

JOSEPH E. STRAKER, JR., OF ATTLEBORO, MASSACHUSETTS, ASSIGNOR
TO WATSON AND NEWELL COMPANY, A CORPORATION OF RHODE ISLAND.

DESIGN FOR A MEDALLION OR SIMILAR ARTICLE.

SPECIFICATION forming part of Design No. 36,689, dated December 22, 1903.

Application filed November 27, 1903. Serial No. 182,912. Term of patent 3½ years.

To all whom it may concern:

Be it known that I, JOSEPH E. STRAKER, Jr., a citizen of the United States, residing in Attleboro, in the county of Bristol and Commonwealth of Massachusetts, have invented a new, original, and ornamental Design for a Medallion or Similar Article, reference being had to the accompanying drawing, forming part of this specification.

- The drawing shows the front view of a medallion embodying my new design.

What I claim is—

The ornamental design for a medallion or similar article as shown.

In testimony whereof I have signed my name in the presence of two witnesses.

JOSEPH E. STRAKER, JR.
